UNITED STATES PATENT OFFICE.

NATHANIEL LEE, OF BRUNSWICK, NEW YORK.

CIDER-PRESS.

SPECIFICATION forming part of Letters Patent No. 325,252, dated September 1, 1885.

Application filed January 14, 1885. (No model.)

To all whom it may concern:

Be it known that I, NATHANIEL LEE, a citizen of the United States, residing in the town of Brunswick, county of Rensselaer, and State 5 of New York, have invented certain new and useful Improvements in Cider - Presses, of which the following is a specification.

My invention relates to cider - presses in which I render it unnecessary to place the 10 pomace upon a platform to be pressed with screws or otherwise, and at the same time to facilitate the work of pressing. I attain these objects as set forth and illustrated in the accompanying drawings, in which—

15 Figure 1 is a vertical section showing a front view of the machine. Fig. 2 is a vertical section of the entire machine. Fig. 3 is a horizontal view of the trough or spout, showing in the end a grooved pulley, the stationary rollers 20 in bottom, and the two diagonal cleats a^2a^3 ; also the endless cloth c , with the rope r' in the center, by which the pomace may be conveyed to the press-wheels R' and R^2 .

25 Similar letters refer to similar parts throughout the several views.

The frame F , as shown in Fig. 1, is the frame on which the press-wheels R' and R^2 revolve up the shafts s' and s^2 , running in boxes b , which are fastened with bolts through the 30 frame F , and which support the gear-wheels $W' W^2 W^3$. The whole may be driven by worm-

screw G , attached to shaft S , as shown in Fig. 2. The boxes b on shaft s' , which support press-wheel R' and gear-wheel W^2 , may be so adjusted that the pressure, as applied by the lever f' , 35 supports weight w and rests upon the fulcrum f^2 , which sets on boxes b . The press-wheel R^2 has two flanges, one on each side, as shown in Fig. 1. The endless cloth C , with the rope r' in the center, as shown in Fig. 2, passes 40 over the groove-pulley p' and through the spout P^2 , in the bottom of which rollers r^2 are placed, and by which the pomace may be conveyed from grater H to between the press-wheels R' and R^2 , and may pass out upon the 45 bracket P' and break down on its sides and rotate back over the pulley p^2 , as shown in Fig. 2, the cider escaping upon the apron s^2 , as shown in Fig. 2.

What I ask for, and claim as my invention, 50 is—

1. The combination of the press-wheels R' and R^2 with the flanges, adjustable boxes b , with levers f' , and weight w , substantially as described.

2. The endless cloth C , provided with rope r' , 55 substantially as described.

NATHANIEL LEE.
